UNITED STATES PATENT OFFICE.

EDWARD A. BUELL, OF DEKALB, ILLINOIS, ASSIGNOR TO SELECTIVE SIGNAL & TELEPHONE MANUFACTURING CO., OF SYCAMORE, ILLINOIS, A CORPORATION OF ILLINOIS.

TELEPHONY.

SPECIFICATION forming part of Letters Patent No. 792,693, dated June 20, 1905.

Application filed October 25, 1904. Serial No. 229,937.

To all whom it may concern:

Be it known that I, EDWARD A. BUELL, a citizen of Canada, residing at Dekalb, in the county of Dekalb and State of Illinois, have 5 invented a certain new and useful Improvement in Telephony, of which the following is a full, clear, concise, and exact description, reference being had to the accompanying drawing, forming a part of this specification.

10 My invention relates to selective signaling appliances, and is of particular utility in connection with telephone - exchange systems from which party-lines extend.

15 My invention has for its object the provision of improved apparatus at the exchange that may be used in coöperation with any suitable selecting and releasing apparatus at each of the substations of a telephone-line.

20 The selective and releasing apparatus that may coöperate with the device of my present invention may be of any suitable character. I do not, therefore, deem an illustration of any such kind of apparatus herein to be essential.

25 In practicing my invention I employ a circuit-changer at the exchange, which is adapted to cause a selected number of impulses of current to be impressed upon the party-line for the purpose of operating the selective devices at the substations. This selective switching mechanism at the exchange may be of any 30 well-known character. In addition to this selective switching mechanism I employ switching mechanism for effecting the release of the substation-selectors. It is my object to provide an interrelation between the releasing switching mechanism and the setting switching mechanism whereby the setting mechanism is maintained in the position to which it

35 40 45 is set until the releasing switching mechanism is operated, which when operated serves not only to effect the release and restoration of the selected devices at the substations, but also to release and permit the return to normal of the selective switching mechanism at the exchange.

In the preferred embodiment of my inven-

tion the selecting switching device at the exchange is preferably in the form of a wheel adapted to be held by a coil-spring, such as 50 a clock-spring, in a zero position. This wheel is provided with a series of projections or elements that intermittently close a circuit including a source of current and the party-line, a handle being preferably fixed to a shaft upon 55 which the wheel is fixed for the purpose of rotating the said wheel against the force of said spring to effect the result desired. A detent is provided for holding the wheel to any position to which it is set, it being understood 60 that the wheel is moved through different angles to effect different selections. The switching device that is operated by the wheel for the purpose of intermittently effecting closure of the circuit that has been specified in turn 65 desirably has its association with the party-line governed by a master-key that is common to a plurality of cord and plug circuits. In one position of the master-key the selective switching mechanism is connected with 70 the party-line, in which position said master-key has no releasing effect upon the detent; but when the said master-key is operated to disconnect the selective switching mechanism at the exchange from the party-line in order 75 that a releasing-current may be sent out over the line the said detent is disengaged from the selective switching device at the exchange, whereupon the said device may be restored to its normal condition or zero position without 80 causing selecting impulses to be sent out over the line, even though the selecting switching device at the exchange is operated.

The association between the detent for the selective switching mechanism and the master-key is preferably effected by means of an electromagnet arranged to operate the detent and included in a circuit controlled by the master-key. This same magnet may, if desired, be of low resistance and may be included in circuit with the battery or other source of current that is included in circuit with the telephone-line in order to effect the release of the selecting devices at the party-

line substations. The same source of current may, if desired, also be used in effecting the operation of the selecting devices at the substations, to which end the battery in releasing the said substation devices is reversed with respect to its connections with the telephone-line when the substation devices are being selectively operated, as is understood to those skilled in the art.

10 I will explain my invention more fully by reference to the accompanying drawing, diagrammatically indicating a party telephone-line extending from a plurality of substations to an exchange, at which exchange there is indicated so much of exchange apparatus as is necessary to an understanding of my invention.

15 The drawing illustrates the preferred embodiment of my invention; but I do not wish 20 to be limited to the precise details of construction herein illustrated, as the invention may be otherwise practiced without departing from its spirit.

25 In the drawing I have indicated a party telephone-line *a a* extending from a plurality of substations A B, &c., and terminating at the exchange in a spring-jack *b*, normally in circuit with a line-indicator *c*. One of many line-jacks *c'* is also indicated, with which 30 the jack *b* may be connected by way of suitable cord-connecting apparatus, which in the instance shown includes an answering-plug *d* and a connecting-plug *e* and cord-strands uniting the tips and sleeves of said plugs, the 35 springs of a listening-key *f* being connected with the said strands and adapted to be moved by the lever *f'* to be connected with the operator's telephone outfit *f''*. Springs of a 40 ringing-key *g* or a key that is adapted to act to open and shut a circuit over which current is to be passed to the line are also indicated in connection with the cord-strands. The alternate contacts of the springs of the 45 key *g* extend to the springs *h* of a master-key, the alternate contacts of which latter springs extend to the selective switch *i*, that is adapted to be intermittently opened and shut by the switch-operating wheel *i'*, normally maintained against a stop *i''* to limit its rotation, 50 while the coil-spring *i'''* is employed to restore the wheel into engagement with the stop *i''*, a handle *i''''* being employed to move the said wheel against the force of the said spring, whereby the lugs or projections *i''''* are successively caused to engage the kinked end *i''''* of the spring *i'''* to bring the said spring intermittently into contact with its companion, whereby current from the battery *k* may be intermittently impressed upon the party-line 55 in the event of the springs *h* being thrust into engagement with their alternate contacts by the lever *l*, the alternate contacts of the 60 springs of key *g* being brought into engage-

ment with said springs by the lever *f'*. The spring *i''* makes the wheel that operates the 65 switching device *i* a self-restoring switch-operating device. The springs *h* and the other springs, which, with them, are associated with the lever *l*, are common to the cord-circuits or cord connectors of one operator's position. 70

The operating-wheel of the switching mechanism is associated with some suitable form of detent element, as the detent *m*, which is so positioned as to engage one or the other of the lugs *i''* to prevent the wheel from being 75 rotated by its spring. It will be understood that the number of lugs or teeth *i''* is not to be restricted and that each time a pin engages *i''* an impulse of current is impressed upon the line acting to operate the selective devices at 80 the substations one step each. The handle that operates the wheel *i'* is desirably elongated to constitute an index *n*, which may register with scale-marks 0 1 2 3, &c., to enable the operator to determine how many impulses of current have been impressed upon the line, the detent *m*, as specified, serving to hold the wheel and the handle in the positions to which they have been set.

85 The preferred form of intermediate connection between the detent *m* and the lever *l* is an electromagnetic connection, to which end the detent *m* is preferably rigidly fixed upon and desirably integrally formed with the armature *n* of an electromagnet *o*, whose helix 95 is included in a circuit that includes the alternate contacts of the key *p* and the springs of 90 said key when the spreader of the lever *l* is moved to the left, the battery *k* being included in this circuit by way of the line *a a*, the 95 spreader of lever *f'* having been moved to the right.

100 It is understood that when the selecting devices at the substations are to be released the spreader of lever *l* is moved toward the left, 105 by which operation not only is the battery *k* included in circuit with the line in a reverse manner to its connection with the line under the influence of the switch *i*, but the said switch *i* is disconnected from the line, for the 110 connection of the said switch *i* with the line is brought about by the movement of the spreader of lever *l* toward the right. When the switch *i* is thus cut off, the line and the 115 releasing impulse is sent over the line to restore the selected devices at the substations thereof, the electromagnet *o*, which then is in series with the battery *k*, is energized to attract its armature, whereupon the detent *m* is withdrawn from connection with the pins *i''*, whereby the spring *i'''* is permitted to restore the 120 wheel with which it is connected, the pins or projections *i''''* failing in their return movement to impress impulses of current upon the line by reason of the disconnection of the switch 125 *i*. Thus the operator only has manually to

rotate the wheel *i* a sufficient distance to impress the requisite number of impulses on the line, the releasing of said wheel being accomplished prior to the next operation thereof, 5 or, if desired, the wheel has only to move a short distance from its previous position to a further position to effect a proper number of impulses. The operator may choose not to restore the wheel, but to move it this additional 10 distance for the next call. However, when a wheel has moved such a distance as to be very near its ultimate position, the wheel is automatically restored by the agency that has been above fully set forth.

15 While I have used this invention particularly for party telephone-lines, I do not wish to be limited in all embodiments of the invention to the uses to which it may be put.

20 While not wishing to be limited to details of construction and arrangement, I claim as new, and desire to secure by Letters Patent, the following:

25 1. In a party telephone-line, the combination with a telephone-line extending from a plurality of substations provided with selective and releasing devices to an exchange, of a switching device for connecting a source of current with a circuit, a self-restoring device serving intermittently to operate said switching device, a master-key for governing the association of said switching device with the circuit upon which it is designed to impress current, a detent normally adapted to hold said self-restoring device in its set position, and an 30 electromagnet included in a circuit controlled by said master-key and governing the operation of said detent to permit the self-restoring device to restore when the switching device is dissociated from the circuit upon which 35 current is to be impressed, substantially as described.

40 2. In a party telephone-line, the combination with a telephone-line extending from a plurality of substations provided with selective and releasing devices to an exchange, of a switching device for connecting a source of current with a circuit, a self-restoring device serving intermittently to operate said switching device, a master-key for governing the association of said switching device with the circuit upon which it is designed to impress current, and a detent normally adapted to hold 45 said self-restoring device in its set position and governed by the master-key to release the said self-restoring device, when the switching device is dissociated from said circuit to permit the self-restoring device to restore, substantially as described.

50 3. In apparatus of the kind described, the combination with a switching device for connecting a source of current with a circuit, of a self-restoring device serving intermittently to operate said switching device, a master-key

for governing the association of said switching device with the circuit upon which it is designed to impress current, a detent normally adapted to hold said self-restoring device in its set position, and an electromagnet included in a circuit controlled by said master-key and governing the operation of said detent to permit the self-restoring device to restore when the switching device is dissociated from the circuit upon which current is to be impressed, substantially as described.

55 4. In apparatus of the kind described, the combination with a switching device for connecting a source of current with a circuit, of a self-restoring device serving intermittently to operate said switching device, a master-key for governing the association of said switching device with the circuit upon which it is designed to impress current, and a detent normally adapted to hold said self-restoring device in its set position and governed by the master-key to release the said self-restoring 60 device, when the switching device is dissociated from said circuit to permit the self-restoring device to restore, substantially as described.

65 5. In a party telephone-line, the combination with a telephone-line extending from a plurality of substations provided with selective and releasing devices to an exchange, of a switching device for connecting a source of current with a circuit, a self-restoring device serving intermittently to operate said switching device, a master-key for governing the association of said switching device with the circuit upon which it is designed to impress current, a detent normally adapted to hold 70 said self-restoring device in its set position, and an electromagnet included in a circuit controlled by said master-key and governing the operation of said detent to permit the self-restoring device to restore when the switching device is dissociated from the circuit upon which current is to be impressed, the switching device serving to impress current upon the line in one direction, while the master-key serves to impress current upon the line 75 in an opposite direction, substantially as described.

80 6. In a party telephone-line, the combination with a telephone-line extending from a plurality of substations provided with selective and releasing devices to an exchange, of a switching device for connecting a source of current with a circuit, a self-restoring device serving intermittently to operate said switching device, a master-key for governing the association of said switching device with the circuit upon which it is designed to impress current, and a detent normally adapted to hold 85 said self-restoring device in its set position and governed by the master-key to release the said self-restoring device, when the

switching device is dissociated from said circuit to permit the self-restoring device to restore, the switching device serving to impress current upon the line in one direction, while
5 the master-key serves to impress current upon the line in an opposite direction, substantially as described.

In witness whereof I hereunto subscribe my name this 22d day of October, A. D. 1904.

EDWARD A. BUELL.
